UNITED STATES PATENT OFFICE.

SAMUEL M. FULTON, OF POMONA, CALIFORNIA.

PUMP-HEAD.

1,357,394.

Specification of Letters Patent. Patented Nov. 2, 1920.

Application filed January 14, 1920. Serial No. 351,480.

To all whom it may concern:

Be it known that I, SAMUEL M. FULTON, a citizen of the United States, residing at Pomona, in the county of Los Angeles, State 5 of California, have invented a new and useful Pump-Head, of which the following is a specification.

This invention relates to pump-heads, and particularly to a structure for driving a plurality of plungers by a variable motion to secure a continuous flow.

The object of the invention is to provide an improved pump operating mechanism designed to occupy a minimum space and including provisions for supporting the crank shaft independently of its journal bearings to relieve said shaft bearings of the weight of, and the downward stress applied to, the crank shaft.

20 Figure 1 is a front elevation of the pump-head, some of the parts being in section, and the well pit, well casing and discharge pipe being shown in section.

Fig. 2 is a top plan view.

25 Fig. 3 is a side elevation.

Fig. 4 is a detailed vertical section through the cross head and pump rods.

Fig. 5 is a detail elevation of the crank shaft.

30 In the drawings 1 designates a foundation preferably formed of concrete and provided with a rectangular well pit 2. Embedded in the concrete foundation with the upper surfaces lying flush with the upper surface of 35 said foundation I provide opposed horizontal tracks, each formed of parallel I beams 3, 4 separated to form longitudinal intermediate slots 5. The beams 3, 4 are held in spaced relation by spacing blocks 6 which are 40 maintained in position by transverse bolts 7, 8 extending through aligned orifices in the beams and in the blocks. The frame which supports the operating mechanism comprises two opposed side frames 9, 10 longitudinally 45 slidable upon the I beam tracks or sills and maintained in spaced relation by a tie bar or yoke 11 secured to the upper forward ends of the side frames. The frame is secured in adjusted position upon the tracks 50 by bolts 12 and nuts 13.

It will be evident that, after disconnecting the operating mechanism from the pump, and after loosening the nuts 13, the frame may be moved on its tracks away from directly over the well, when desired.

55 The main drive shaft 16 is journaled in

the bearings 17, 18 in the rear portions of the side frames 9, 10 and has fixed to one end, beyond the side frame 10, a belt wheel 19 which is driven by a motor 20 through a 60 belt 21. A belt tightening device such as is indicated at 22 may be employed if desired. A crank shaft 23 is journaled in bearings 24, 25 in the forward portions of the side frames 9, 10 and has fixed to one end, beyond the 65 side frame 9, a gear wheel 26 which meshes with a gear pinion 27 fixed to the main shaft 16. (See Fig. 2.) The crank shaft is formed with crank arms 28, 29 adjacent each side frame and connected by crank pins 30, 31 respectively, to crank disks 32, 33, the disks also being connected by a central crank pin 34. (See Fig. 5.) The crank disks rest upon relatively aligned rollers 35, 36 which are carried by a shaft 37. Said shaft is journaled in bearing blocks 38-38 carried by the side frames. This structure provides a support at the medial portion of the crank shaft to relieve the crank shaft bearings of the major portion of the load of the working 80 strokes of the pump.

Journalized in bearings 40-41 at the rear portions of the side frames is a beam shaft 42 on which are journaled three walking beams 43-44-45, each having a bearing 46 engaging the shaft and secured in position by evaporating bearing caps 47. As the three walking beams are of duplicate construction, a description of one of them will herein suffice. Each beam comprises a 90 skeleton frame forming parallel slide ways 50-51, in which slides a crank pin block 52, the slide block of each beam respectively cooperating with its companion crank-pin of the crank shaft. The beam frame is also 95 provided with an orifice 53 providing clearance for non-interference with the main drive shaft 16 which projects through said orifice and the forward end of said frame has a pivoted bearing 54 for connection with 100 the pump.

A vertical guide rod 75 is detachably clamped in the outer medial portion of the tie yoke 11 and is secured in any desired manner at its lower end, for instance, by 105 being screw-threaded into the flange 76 of the well-head, as shown in Figs. 1-3. The flange 76 is angularly disposed relative to the rod 75 and is secured to the well-head 110 77 by bolts 78, the well casing and tube being attached to said head in any suitable manner with the tube communicating with

the discharge pipe 79. This construction of well-head provides a discharge having a gradual bend free from sharp turns as would retard the flow.

- 5 Links 80—81 are pivotally connected at 54 to the center walking beam 44 and to a guide head 82 secured to the upper end of an inner pump rod 83 which extends downwardly in telescopic engagement within an outer tubular pump rod 84. The guide head 82 has a split bearing 85 slidably engaging the guide rod 75, and by which the pump rod 83 is guided in its reciprocating movements.
- 15 The two outer walking beams 43—45 are respectively connected by links 86—87 to opposite sides of a cross-head 88 which is secured to the top of the tubular pump rod 84 (see Fig. 4) a suitable packing being 20 provided between the cross-head and inner pump rod 83, as indicated at 89.

In operation, the drive shaft 16 being driven at a uniform rate of speed rotates the crank shaft 23 through the medium of 25 the gear pinion 27 and gear wheel 26, the crank pins of the crank shaft being journaled in the slide blocks and the slide blocks slidable in their respective walking beam slide ways. As the two outside crank pins 30—31 are coincidentally alined, the outside walking beams 43—45 will operate in unison to reciprocate the outer tubular pump rod, and as the center crank pin 34 is positioned diametrically opposite to the 35 pins 30—31, the walking beam will reciprocate the inner pump rod in opposite directions. The ends of the strokes to which the oppositely positioned crank pins raise or lower their respective walking beams are 40 indicated by dotted lines *a—b* on Fig. 3 and as these positions are relatively angularly disposed, it follows that, when one pump rod reaches the end of a stroke the other pump rod has already started some distance 45 on the next stroke, thereby producing a stroke lap in the operation of the pump rods, which insures a continuous pumping operation.

The invention herein described provides 50 a pump head mechanism which as a unit may be readily moved from its normal position over the well pit to a position which will afford free access to said pit, also by positioning the entire operating mechanism 55 between the two side frames the width of the pump connections extending into the pit is reduced to a minimum so that the supporting beams may be closely positioned together to afford a sturdy compact structure especially adaptable for use in wells in 60 which it is undesirable or impossible to pro-

vide well pits of large dimensions. The provision of the supporting rollers for carrying the weight of the crank shaft insures long life to the crank shaft bearings and 65 guards against any distortion of the shaft.

I claim:

1. In a pump-head, parallel walking beams, a crank shaft having opposed crank arms, intermediate crank disks and crank pins connecting the adjacent arms and disks, rollers supporting the crank disks, and slide blocks engaging the crank pins and walking beams. 70

2. In a pump-head, parallel walking beams having longitudinal slide ways, a crank shaft having opposite crank arms, intermediate crank disks and crank pins connecting the adjacent arms and disks, rollers supporting the crank disks, and slide blocks 80 journaled on the crank pins and slidable in the slide ways. 75

3. In a pump-head, opposed side frames, pivoted parallel walking beams positioned between said frames and having longitudinal slide ways, a crank shaft having crank arms adjacent each side frame, crank disks between the crank arms and crank pins connecting the arms and disks, rollers supporting the crank disks, and slide blocks 90 journaled on the crank pins and slidable in the slide ways. 85

4. In a pump-head, a drive shaft, a crank shaft, and a pivotal bearing rod, a frame providing journal bearings for said shaft, 95 a walking beam in operative connection with the crank shaft, and independent means for supporting the crank shaft.

5. In a pump-head, opposed side frames, an operating mechanism including a crank 100 shaft and positioned entirely between the side frames, and independent means between the frames for supporting the crank shaft.

6. In a pump-head, opposed side frames, 105 an operating mechanism including a crank shaft having a crank disk and entirely positioned between the side frames, and an independent means engaging the crank disk to support the crank shaft. 110

7. In a pump head, an operating mechanism including a crank shaft, opposed side frames providing journal bearings for said shaft, and means independent of the journal bearings for supporting the shaft. 115

Signed at Pomona, California, this 7th day of January, 1920.
